PERMANENT MAGNET BLOWOUT FOR
ELECTRIC SWITCHES

Konrad Heinrich, Milwaukee, Wis., assignor to
Allen-Bradley Company, Milwaukee, Wis., a
corporation of Wisconsin

Application January 13, 1941, Serial No. 374,175

3 Claims. (Cl. 200—147)

This invention relates to an improved permanent magnet blowout for electric switches and particularly to a permanent magnet blowout suitable for use in a multiple break straight line motion switch of the enclosed arc chamber type.

The object of this invention is to secure an arrangement for a magnetic blowout associated with switch contacts operating in an arc chamber whereby the blowout force is so directed that the arcs occurring between contacts are effectively directed away from the contacts and toward a side wall of the arc chamber regardless of the direction of flow of current through the contacts or the polarity of the blowout.

A further object is to secure a new structural arrangement for a magnetic blowout whereby blowout action is secured for a plurality of switch contacts by the use of a single blowout.

A further object is to secure improved blowout action in a multiple break straight line motion switch of the enclosed arc chamber type by the use of a single permanent magnet uniquely positioned and proportioned to effectively increase the disrupting capacity of the switch.

A further object is to secure improved blowout action in a multiple break straight line motion switch of the enclosed arc chamber type by the use of a unique bar magnet having like poles at each end and a common pole in the center.

The trend of design in industrial electric control switches is toward small compact structures. Multiple break switches operating in an arc-resisting enclosure have been designed to meet the demand for compactness and high interrupting capacity. This design has been utilized in the straight-line motion switch to great advantage. Any changes in the design of a switch that increase the interrupting capacity without increasing the size of the switch are of material value if the change does not entail an excessive additional cost. The blowout magnet structure disclosed in this invention materially increases the safe interrupting capacity of the switch.

The invention discloses a simple structural arrangement for a permanent magnet blowout in which the magnet is spaced within the arc resisting enclosure so as to effectively increase the interrupting capacity of the switch. In a two-pole double break switch this change is accomplished in the preferred form disclosed by three simple changes in structure. A recess is formed in the arc enclosure for the blowout magnet, the locking bolt for the arc enclosure is changed from steel to brass and a permanent bar magnet is provided to secure blowout action. This single

5 magnet serves as a blowout for all contacts thus utilizing in a very efficient manner the magnetic field of the magnet. With this change the safe interrupting capacity of each double break contact on direct current is increased from six (6) amperes to three hundred and twenty five (325) amperes when interrupting a resistor load at 220 volts.

10 The preferred form of this invention is described in detail in the following specification and attached drawings in which:

Figure 1 is a front view of the preferred switch structure showing the location of switch contacts, arc resisting enclosure and blowout magnet with portions of the arc resisting enclosure in section to show the structural relation of the parts;

Figure 2 is a sectional view taken along the lines 2—2 in Figure 1;

Figure 3 is a perspective view showing the principal elements of this invention with the outline of the arc enclosure shown in a phantom view by means of broken lines;

Figure 4 is a diagrammatic view showing the location of the contacts, arc chamber, blowout magnet and the resulting magnetic field set up by the blowout magnet with the direction of the blowout action designated by means of arrows; and

Figure 5 is a diagrammatic view, similar to that 15 shown in Figure 4, in which an alternate form of blowout magnet is used.

In the specific example disclosed as illustrative of this invention, the blowout magnet is shown incorporated in a switch structure such as that 20 described in Patent No. 2,071,149 issued to Gustav O. Wilms et al., February 16, 1937. The construction of the arc hood 2 as shown in Figures 1 and 2 comprises a back section 3, front section 4 and top section 5 that interfit to form two restricted 25 arc chambers 10. The back section 3 is mounted to a supporting plate 1 by means of screws 7 and brass bolt 6. The brass bolt 6 also serves as a means to lock together the back section 3, front section 4 and top section 5 and as a retaining 30 means for the blowout magnet 9. Four stationary contacts 12 are mounted on top section 5 whereby two stationary contacts 12 are spaced within each of the two restricted arc chambers 10 as shown in Figure 2. In the bottom of each arc chamber 10 there is an opening 11 for the bridging contact actuator 17 clearly shown in Figure 3.

The complete actuator assembly 19 comprising cross bar 15, two bridging contact carriers 17 and two bridging contacts 13 is movable along

the "line of movement" designated in Figure 3. Each bridging contact carrier 17 is attached to cross bar 15 and the free end of each bridging contact carrier 17 supports a bridging contact 13. Each bridging contact 13 includes two contacts 14 that cooperate upon movement of the actuator assembly 19 to the closed position to engage the oppositely positioned stationary contacts 12.

The top section 5 of the arc hood enclosure 2 is formed with a recess 8 spaced midway between each pair of stationary contacts 12. Into this recess there is inserted a permanent magnet 9, which in the assembled structure, is maintained in the recess by the brass bolt 6. The permanent magnet 9 used in this structure is of the "Alnico" type which has been found to be very efficient for this purpose.

The complete structural arrangement of the principal elements essential to this invention are clearly shown in Figure 3 which shows by means of a perspective view the arrangement of the stationary contacts 12, permanent magnet blow-out 9 and cooperating movable contacts 14. These are shown in solid line with the arc resisting enclosure 2 and openings 11 shown in a phantom view by broken lines. The exact structural detail of the actuator assembly 19 and its assembled parts are not described in this specification. These details of construction do not constitute a part of the patentable subject matter of this application.

To further explain the blowout action resulting from the structure disclosed, a diagrammatic view showing the location of each pair of stationary contacts 12 in each of the restricted arc chambers 10 and blowout magnet 9 is shown in Figure 4. The two stationary contacts 12 designated "Line" represent the incoming direct current lines marked plus and minus and the two stationary contacts 12 designated "Load" show the outgoing side of the direct current lines marked minus and plus. Spaced midway between each pair of stationary contacts 12 and midway between the restricted arc chambers 10 is a blowout magnet 9 having at one extremity a north pole and at the opposite extremity a south pole. The four stationary contacts 12 and bar magnet 9 lie substantially in the same plane and there is designated in this diagram the magnetic field resulting from the blowout magnet 9. The field in this plane common to both the stationary contacts 12 and the bar magnet 9 is herein designated as a magnetic plane. With the current flowing through the contacts in the direction indicated by means of the plus and minus signs as given in Figure 4 and with the blowout magnet 9 located in the designated position, the force effective to distend the arcs that occur upon interruption of an electric current is in the direction indicated by means of arrows shown on the diagram. At each contact the arc is distended in a direction substantially at right angles to the line of motion of the switch and to impinge upon a wall of the arc chamber.

In order to cause the arc to more directly impinge upon the side wall of the arc chamber 10, it is found desirable to utilize a bar magnet having a length equal to or greater than the spacing of the contacts. The use of an excessive length is impractical because it is impossible to totally 70 enclose the bar magnet in the arc resisting enclosure without increasing the size thereof. It has also been found to be quite advantageous to use a modified bar magnet such as that shown in a similar diagram given in Figure 5 where the 75

bar magnet 16 has extreme poles of like polarity with a common pole in the center of the bar magnet as shown in Figure 5. By using a bar magnet 16 of this construction, herein designated as a three pole magnet, it is possible to have the arc impinge almost directly upon the side wall of the arc chamber. The direction in which the arcs are distended with a magnet of this type is designated in Figure 5 by means of arrows.

The magnetic axis of the magnet as shown in Fig. 4 extends between its polar faces, namely N and S and corresponds substantially to the length of the magnet. The magnetic axis of the magnet as shown in Fig. 5 extends between its polar faces, namely N and N and corresponds substantially to the length of the magnet.

In either of the two forms shown in Figures 4 and 5 the blowout force effective to distend the arcs occurring between cooperating contacts is directed toward a side wall of the arc chamber and effectively away from the contacts enclosed by the arc chamber. This feature remains unaltered even though the polarity of the conductors or magnet is reversed. For best operation of a switch of this type it is essential that the arc be directed to contact a closely adjacent side wall of the arc chamber to assist in extinguishing the arc and effectively away from the contacts enclosed by the arc chamber to avoid the formation of a single short circuiting arc between the two stationary contacts.

In the preferred form shown, the pair of stationary contacts 12 are spaced within each of the two restricted arc chambers 10 and cooperating therewith is a bridging contact member 13 arranged to engage and disengage each pair of stationary contacts 12 for the purpose of making and breaking an electrical circuit therethrough. In order to provide blowout action and to obtain a simple compact structure, a bar shaped permanent magnet 9 is placed symmetrically between each pair of contacts and spaced from and parallel to the plane of movement of both bridging contacts 13. The bar magnet 9 is also located so that the plane of movement of each bridging contact member is perpendicular to a magnetic plane of the permanent magnet 9 and with the magnetic plane passing substantially through the points of contact of the switch. This position 50 for the blowout magnet centrally located with respect to the four contact positions is unique in that blowout action for four contacts is secured from one magnet. The insertion of the magnet within a recess in the arc enclosure permits of the addition of a magnetic blowout without the usual increase in size of the switch.

In the switch structure disclosed the magnetic blowout is a permanent magnet. Compact switch structures of the type disclosed can be more easily equipped with a magnetic blowout in the form of a permanent magnet than the more cumbersome electromagnetic blowout. There are, however, switch structures in which an equivalent electromagnetic blowout can be incorporated that will utilize the inventive concept of this disclosure.

What I claim as my invention is:

1. In an electric switch comprising two spaced stationary contacts and a bridging contact member disposed in a single arc chamber with said bridging contact member arranged for movement in a given plane to cooperate with said stationary contacts to make and break an electric circuit therein, the electric current to be controlled entering a stationary contact thence to the bridging contact and out through the other stationary con-

tact in a path substantially a U, the combination with said switch elements of a permanent magnet of bar shape having a north pole on one end and a south pole on the other end and positioned exteriorly and adjacent said arc chamber with the longitudinal axis of said bar parallel to the plane of said motion of said bridging contact and with each end of said bar adjacent a set of cooperating contacts to cause said arcs occurring on opening of contacts to be distended laterally of a line joining the stationary contacts.

2. In an electric switch comprising two spaced stationary contacts and a bridging contact member disposed in a single arc chamber with said bridging contact member arranged for movement in a given plane to cooperate with said stationary contacts to make and break an electric circuit therein, the electric current to be controlled entering a stationary contact thence to the bridging contact and out through the other stationary contact in a path substantially a U, the combination with said switch elements of a permanent magnet, three-pole type, of bar shape having like poles at each end thereof and positioned exteriorly and adjacent said arc chamber with the longitudinal axis of said bar parallel to the plane of said motion of said bridging contact and with each end of said bar adjacent a set of cooperating contacts to cause said arcs occurring on

opening of contacts to be distended laterally of a line joining the stationary contacts.

3. In an electric switch comprising four stationary contacts rectangularly spaced in one plane, two spaced parallel bridging contact members each cooperating with a pair of said stationary contacts to make and break an electric circuit therethrough, an enclosure to provide a separate arc chamber for each set of stationary contacts and its cooperating bridging contact member, the electric current to be controlled entering the stationary contact, thence to its associated bridging contact member, and out through the associated stationary contact and through the other stationary contacts and bridging contact member in like manner, the combination with said electric switch of a permanent magnet of bar shape positioned in the wall of said enclosure intermediate said two chambers with its longitudinal axis parallel to the lines joining each of said pairs of stationary contacts and said magnet of such length to have each end adjacent a stationary contact of each of said pairs, the magnetic lines of said bar magnet to direct the arcs upon interruption of electric current flowing through the contacts toward a wall of the enclosures and effectively away from the respective contacts.

KONRAD HEINRICH.
